UNITED STATES PATENT OFFICE

135,658

DESIGN FOR A FLAG

William S. Bailey, Irvington, N. J.

Application February 4, 1943, Serial No. 109,447

Term of patent 7 years

To all whom it may concern:

Be it known that I, William S. Bailey, a citizen of the United States, residing in the city of Irvington, county of Essex, and State of New Jersey, have invented a new, original, and ornamental Design for a Flag, of which the following is a specification, reference being had to the accompanying drawing, forming a part thereof.

The figure is a front elevational view of a flag showing my new design.

I claim:

The ornamental design for a flag, as shown.

WILLIAM S. BAILEY.
